UNITED STATES PATENT OFFICE.

MURT J. DOWLING, OF STEWARTSVILLE, NEW JERSEY.

RAILWAY-TIE.

967,176.

Specification of Letters Patent. Patented Aug. 16, 1910.

Application filed November 15, 1909. Serial No. 528,179.

To all whom it may concern:

Be it known that I, MURT J. DOWLING, a citizen of the United States, residing at Stewartsville, in the county of Warren and 5 State of New Jersey, have invented a new and useful Railway-Tie, of which the following is a specification.

This invention relates to railway ties and to rail fasteners for use in connection 10 therewith and one of its objects is to provide a reinforced concrete tie having means whereby the desired resiliency is retained.

Another object is to provide a tie of this 15 type having improved means for fastening rails thereto, the same being of a simple and durable nature, easy to apply and adjust.

With these and other objects in view the invention consists of certain novel details of construction and combinations of parts here- 20 inafter more fully described and pointed out in the claim.

In the accompanying drawings the preferred form of the invention has been shown.

25 In said drawings, Figure 1 is a perspective view of a portion of a tie embodying the present improvement, the rail being shown secured in position upon the end portion thereof. Fig. 2 is a plan view of one 30 end portion of a tie, the rail fastening devices being removed. Fig. 3 is a trans- 35 verse section through the tie and showing, in elevation, one set of bolts used in connection with the fastening devices. Fig. 4 is a central vertical transverse section through the tie. Fig. 5 is a detail view of one of the 40 securing bolts. Fig. 6 is a perspective view of a modified form of rail chair.

Referring to the figures by characters of 45 reference 1 designates an I-beam embedded within a concrete body 2 which preferably increases in width toward the bottom thereof, the top face of the beam being flush with the corresponding face of the body and the longitudinal corners of said 50 body being preferably cut-away or beveled as shown at 3. Oppositely disposed aline- 55 ing transversely extending slots 4 are formed within the top of the beam 1 adja- cent each end of the tie, these slots register- 60 ing with corresponding grooves 5 formed within the concrete body thereunder, the grooves however being of greater width 65 than the slots. Diagonally disposed slots 6 are formed within the top portion of the I- 70 beam at points between the slots 4 and the

75 adjoining ends of the tie, these slots 6 being disposed above corresponding grooves 7 formed in the concrete body and which are of greater width than the slots 6. The arrangement of slots has been clearly indicated in Fig. 2.

80 A depression 8 is formed in each side of the tie body 2 at the center thereof and a slot or incision 9 extends into the tie body at its center, said slot projecting into the sides and bottom of said body and close to the beam 1 there being preferably a thin shell 8 of concrete constituting the inner walls of the slot and serving to protect the 85 adjoining portions of the I-beam from the action of moisture and air.

80 The rail fastening means used in connection with this tie consists of a base plate or chair 10 seated on a cushion 10' of a suitable fibrous material and having a longitudinally extending flange 11 so shaped as to extend over and firmly engage one of the base flanges of a rail A. Openings 12 are formed in this plate near each end thereof, 90 one set of openings being designed to receive bolts 13 each of which has a longitudinally extending rib 14 adjacent the head 15 thereof, one end of the said bolt being threaded to receive a clamping nut 16 as 95 shown in Fig. 5. The head 15 of the bolt is insertible into the groove 7 under one of the slots 6 and the shank and rib of the bolt are disposed to rest within the slot 6, the rib serving to hold the bolt against rotation. 100 The threaded portion of the bolt extends through the base plate and a nut 16 serves to clamp said plate upon the top of the tie. One of these bolts is insertible into each of the grooves 7 and 5, those of the bolts which 105 project through the slots 4 being designed not only to extend through the base plate 10 but also to extend through a holding plate 17 which is designed to rest upon the base plate and which has a flange 18 so shaped and located as to extend over and firmly engage one of the base flanges of the rail A.

110 From the foregoing description, when read in connection with the accompanying drawings, it is believed that the manner of securing rails to the tie will be clearly understood.

The base plates 10 are placed upon the tie body after the bolts 13 have been slid into 115 the grooves 5 and 7 and the slots 4 and 6 and the said bolts are extended through the

base plate, two of them being secured thereto by means of nuts so as to clamp the plates upon the tie while the other two are extended through the holding plate 17 and 5 then secured. The flanges of the rail A will thus be tightly held by the flanges 11 and 18 of the two plates as shown in Fig. 1. When the tie is placed within the roadbed it is prevented from creeping longitudinally 10 because portions of the material constituting the roadbed project into the recesses 8. Moreover in view of the fact that the slots 9 are extended into the middle portion of the tie body, said tie is capable of being 15 flexed to a certain extent, this flexing being sufficient to give the desired resiliency.

It will be seen that the entire tie is very simple and durable in construction and that the rail fastening can be readily applied 20 thereto and will securely hold the rails in position.

Where a fastener such as herein described is located at a rail joint, the flange 19 on the base plate 20 is preferably provided with a 25 web 21 designed to engage the fish plate,

there usually being a notch in the base portion of the same into which this web may fit. This form of base plate has been illustrated in Fig. 6. The holding plate can be provided with a similar web.

30

It is of course to be understood that various changes may be made in the construction and arrangement of the parts without departing from the spirit or sacrificing any of the advantages of the invention.

35

What is claimed is:—

A railway tie including a plastic body and a metallic reinforce extending longitudinally therein and having an exposed upper face, there being recesses within opposite faces of the body and a slot extending into the body from said recesses and close to the reinforce.

40

In testimony that I claim the foregoing as my own, I have hereto affixed my signature in the presence of two witnesses.
